UNITED STATES PATENT OFFICE.

CHARLES M. ADAMS AND GEORGE W. ADAMS, OF PROVIDENCE, RHODE ISLAND.

JEWELER'S PRESS.

SPECIFICATION forming part of Letters Patent No. 530,915, dated December 18, 1894.

Application filed December 26, 1893. Serial No. 494,717. (No model.)

To all whom it may concern:

Be it known that we, CHARLES M. ADAMS and GEORGE W. ADAMS, of Providence, in the county of Providence and State of Rhode Island, have invented certain new and useful Improvements in Jewelers' Screw-Presses; and we do hereby declare that the following is a full, clear, and exact description thereof, reference being had to the accompanying drawings, and to the letters of reference marked thereon, which form a part of this specification.

This invention relates to that class of screw presses used for stamping sheet metal, and which are called "jewelers' presses." Its object is to accomplish with one motion of the screw, the two operations of punching the blank from the sheet metal, and drawing that blank into a cup. It is fully illustrated in the accompanying drawings.

Figure 1, is a front elevation of the press. Fig. 2, shows a vertical section of the press, taken through from front to back on line *x*, *x*, Fig. 1. Fig. 3, shows a punched washer. Fig. 4, is a perspective view of a cup finished. Fig. 5, shows a vertical cross section of a cup. Fig. 6, shows in section, the punching devices seen in Fig. 2, with the punches lower down. Fig. 7, is a horizontal section of the plungers that hold the punches, on line *y*, *y*, Fig. 2. Fig. 8, represents a face view of the lower end of the inner plunger. Fig. 9, shows a front elevation of the inner plunger, separate.

As before stated, the object of the invention is to accomplish the punching out of the blank and the drawing of it out to form a cup, at one operation. In the screw presses that jewelers' use, a blank or washer is first punched out by a partial turn of a screw, and my improvement enables the operator to draw the blank into a cup, without removing it from the die, by continuing the motion of the screw a little farther around. This saves at least one-half of the time over the usual way of changing the cutting punch for a drawing punch, and feeding the blanks previously punched, into the die one at a time by hand. There is not so much motion of the screw required in performing the two operations at once, as is necessary in drawing the washers after they are

punched in the usual way, for in feeding the blanks into the die by hand, the punch must be raised high enough to let the fingers pass under it, while in punching and drawing at the same time, the punch is only required to rise sufficiently high to allow the sheet metal at one operation, for the blank is more accurately centered for the drawing punch at the time they are punched out, than when separately put in the die by hand.

The construction is as follows:

A, is the standard of the press; *B*, the screw nut, and *L* the working screw.

D, is an outer plunger for holding the washer punch *b*. The plunger *D*, is fitted to slide in ways *a*, *a*, cast on or otherwise attached to the face of the standard *A*, and the plunger *F*, is fitted to slide in a chamber made through the plunger *D*, and is connected to the screw *L*, by a split collar *c*, screwing into the upper end of the plunger.

The plunger *F*, is recessed in at its lower end at *j*, (see Figs. 8 and 9) to hold the drawing punch *d*. The recess *j*, is carried in beyond the center of the plunger, as shown by the dotted lines in Fig. 8, to receive the flanged head of the punch *d*, and a hole *s*, is made in the center to receive the stem of the punch. The manner of inserting this punch in its place, is as follows: Before the punch socket *b*, is put into the end of the plunger *D*, the head of the punch *d*, is passed up inside the plunger *D*, into the wide part of the recess *j*, and then pushed back into the center of the plunger until the stem of the punch is in the hole in the center of the plunger *F*. In this position the punch *d*, is held securely to move up or down with the plunger. Then the socket *b*, that holds the washer punch *g*, is put into the end of the plunger *D*, and fastened by the set screw *h*, in the side of the plunger *D*. See Fig. 2. The washer punch *g*, has a hole through its center to receive and guide the drawing punch *d*, and the punch *g*, is held in the socket *b*, by a set screw *l*, in the socket. The inner plunger *F*, has a spline at *m'*, fast in it, fitting in a slot in the other plunger to prevent it from turning. The plunger *F*, and its

punch *d*, are moved by the screw independent of the plunger *D*, which moves only when locked to the plunger *F*.

The locking devices are constructed as follows: A recess *i*, is made through the front of the plunger *D*, and a little projection *f*, is made just below the opening *i*. A block *n*, is fitted to slide in the recess *i*, and its ends are beveled off at *o*, *o*. The recess *i*, is made 10 narrower above the block *n*, so that its sides will project over that block, and prevent it from rising in the recess. A recess *a'*, is made in front of the plunger *F*, near the top, leaving the part *v*, projecting out the full 15 size of the plunger; but the space *m*, between the recess and the upper end of the plunger, is planed off enough to be below the part *v*, and the upper edge *n'*, of the recess, is beveled off at the same angle as the corners *o*, 20 of the block *n*. A plate *C*, is attached to the head of the standard in front, by means of the bolt *t*, which passes through a slot in the plate and screws into the head of the standard. The plate *C*, extends down in front of 25 the press, to about the middle of the plunger, and has its lower end turned square in toward the plunger, to form a ledge *p*. A recess *r*, is cut out of the inner side of the plate *C*, just above the ledge *p*, and has its 30 upper edge beveled off to like angle as the corners *o*, of block *n*. The outside of the nut *B*, above the flange by which it is fastened to the standard *A*, has a screw thread made on it, and a collar *J*, split through on 35 one side, with a vertical flange on each side of the split, has a screw thread made on its inside, fitting into the thread on the nut, and a bolt *s'*, passing through the two flanges, serves to close and tighten the collar on the 40 nut wherever it may be set. This collar is set to limit the distance the screw can be turned down.

The operation is as follows: With the parts in position as shown in Fig. 2, by turning the 45 screw *L*, the plunger *F*, is carried down and carries with it the plunger *D*, by the block *n*, the inner end of which projects into the recess *a'*, in the plunger *F*. This block *n*, is prevented from being pushed out by the beveled surface, 50 because of its outer end bearing against the inner face of the plate *C*, until the plunger *D*, has gone down far enough for the block *n*, to be pushed out of the recess *a'*, into the recess *r*, and the block *n*, will bring up against 55 the ledge *p*, and the motion of the plunger *D*, will be stopped thereby. The point at which the plunger stops, is when the punch *g*, has just cut through the sheet metal, and the plate *C*, can be set by means of the slot and 60 bolt *t*, at any desired point for this purpose;

but the continued motion of the screw *L*, carries the plunger *F*, down farther, as the low space *m*, on the plunger, allows its upper end to pass the block *n*, until its punch *d*, has passed down into the blank cut by punch *g*, 65 the distance necessary to form the cup. The return motion of the parts is in this way: The motion of the screw *L*, being reversed, the plunger *F*, will be drawn up until the lip *v*, catches under the inner end of the block *n*. 70 This will begin to carry the block *n*, and plunger *d*, up, and the outer end of the block *n*, will be pushed clear into the recess *a'*, by the bevel on the recess *r*. This brings all parts 75 in position, as when the operation described began. By setting the plate *C* lower down, the block will be held from being pushed out and the press can be used as a single acting one.

Having thus described our improvements, 80 we claim as our invention—

1. In a screw press, two plungers or mandrels with punches, operated by the same screw, in combination with said screw, substantially as described. 85

2. In a screw press, the combination of two sliding punches operated by the same screw, and means for connecting one of said punches with the other punch, and for disconnecting it from said punch, and means for locking 90 said punch when so disconnected, to prevent its further motion, substantially as set forth.

3. In a screw press, the combination of two sliding plungers, one working inside the other and operated by one screw, the inner plunger being recessed in its lower end as described to hold a drawing punch, a socket in the outer plunger holding a cutting punch, said cutting punch having a hole through it to receive the drawing punch, substantially as described. 95 100

4. In a screw press, the combination of two sliding punches operated by the same screw and sliding one in the other, the outer plunger having a recess through it, and a recess in the front of the inner plunger having projecting 105 edges at the lower edges of the recesses in the plungers and the upper side of the recess in the inner plunger beveled away, a front plate adjustably attached to the press standard and having a recess in its lower end the bottom of which projects inward and the upper side of which is beveled away, a block fitted to slide in the recess in the outer plunger and having its ends beveled, substantially as described. 110
